UNITED STATES PATENT OFFICE

2,172,401

BOAT PROPELLING DEVICE

Nels H. Nelson, Minneapolis, Minn.

Application July 12, 1937, Serial No. 153,127

7 Claims. (Cl. 115—18)

My invention relates to improvements in boat propelling devices.

In many localities, in numerous pursuits, and at the hands of many users, the conventional, engine powered outboard propelling devices for boats fail to meet the requirements because of excessive original costs, maintenance costs, non-availability of fuel and lubrication supply and lack of ready portability.

10 An object of my present invention is to provide a simple, durable, readily portable, and relatively inexpensive hand powered outboard propelling device for small boats, adapted to be easily attached to and detached from such boats and capable of efficiently propelling and steering the same.

15 A further object of the invention is to provide a boat propelling device having a propeller and a revolute driving member therefor adapted to be turned by hand and bodily swung from side to side to swing said propeller into various steering positions, another object of the invention being to provide means for stationing the hand driving member, selectively, in the various positions into 20 which it may be swung and to supply additional independently operable means for swinging the propeller into various steering positions.

25 Another object of the invention is to provide a revolute hand driving member consisting of a wheel formed with an annular hand grip along which the hand may be shifted from point to point for progressively renewing the grip and to further provide means for readily converting such member into a driving crank for uninterrupted 30 grasp by the hand of the user.

35 A still further object of the invention is to supply a hand driving member, as above, having a pair of coaxially disposed hand wheels, one for each hand, whereby upon the alternate application 40 of the hands of a user to their respective annular hand grips, an uninterrupted transmission of power to the propeller is attained and uninterrupted control of the propeller as a steering medium provided.

45 Other objects of the invention reside in the novel combination and arrangement of parts and in the details of construction hereinafter illustrated and/or described.

In the drawings, Fig. 1 is a side elevational view of an embodiment of my invention; Fig. 2 is another elevational view thereof, the same being taken from the front of the device; Fig. 3 is a vertical central sectional view of the lower portion of the device and illustrates the propeller 50 and rudder mounting; Fig. 4 is a vertical, central

5 sectional view of the upper portion of the device and illustrates the mechanism for transmitting power from the hand wheels to the countershaft through which the propeller is driven, also the construction by means of which the propeller is 5 swung from side to side independently of the hand wheels; Fig. 5 is a detail sectional view taken as on the line 5—5 of Fig. 1, but drawn to a larger scale, and Fig. 6 is a detail sectional view taken on the line 6—6 of said Fig. 1 and drawn to a 10 larger scale.

Reference being had to the accompanying drawings, it will be seen that my invention embodies a structure generally similar in type to the conventional engine driven outboard propelling 15 mechanisms used on small boats. My improved device includes a tubular body A having a mounting B therefor by means of which said device is clamped to the stern of a boat with said tubular body normally in substantially upright position. 20 At the upper end of the tubular body A and offset therefrom are a pair of hand wheels 10, while at the lower end of said body A, is a propeller 42. The propeller 42 is connected with the hand wheels 10 so that it is rotated when said hand wheels are revolved and is swung one way or the other upon a corresponding swinging movement 25 of the hand wheels 10.

The mounting B includes an anchoring clamp 12 and a split sleeve 13 carried thereby, said sleeve 30 13 receiving the tubular body A and being partially cut away medially thereof at its open side. At each end portion of the split sleeve 13 are paired lugs 14 through which a clamping bolt 15 is passed, said bolt being free to turn in one of the lugs, but threaded in the other lug. Each of the clamping bolts 15 has a finger piece 16 to facilitate the turning thereof. With these bolts 15 loosened sufficiently, the tubular body A may turn in said sleeve 13, under greater or lesser restraint, as desired. Abutment collars 17, encircling the tubular body A and adjustably secured thereto by means of screws 18 in positions above and beneath the split sleeve 13, provide for the lengthwise adjustment of said body A with 35 respect to said sleeve 13 for purposes later to appear. The clamp 12 has two end members 19 connected together in spaced relation by means of webs 20, 21, each end member being of inverted U-shaped formation and having an ear 22 thereon. These ears 22 are apertured to receive a 40 pintle 23 which passes through an aperture in a boss 24 formed at the upper end of the split sleeve 13 at the closed side thereof, said pintle 23 serving as a pivoting medium between clamp 12 and sleeve 45 50 55

23. The clamp 12 receives an upstanding portion 5 of a boat between the front and rear legs 25, 26 of its end members 18. The rear legs 26 provide abutments for engagement with the outside of the boat and the front legs 25 are provided with clamping screws 27 fitted with finger pieces 28, said screws serving to engage the inside of the boat and rigidly secure the clamp 12 in position on the boat structure. Pivoted to the rear leg 26 of one of the end members 18 of the clamp 12 is a quadrant 29, the same being slotted lengthwise thereof as at 30. Passing through the slot 30 in said quadrant 29 is a clamping screw 31 which is threaded in a boss 32 issuing from one side of the split sleeve 13. This boss 32 provides an abutment for the inner face of the quadrant 29 and the screw 31 has a head 33, fitted with a finger piece 34, said head being adapted to engage the outer face of said quadrant. Thus, by means of 15 said quadrant 29 and clamping screw 31, the tubular body A of the device may be disposed in an upright position or in certain relatively inclined positions, as the hereinafter described uses of the device may require.
25. A tubular stem 35 received within the tubular body A and extending the full length thereof projects from said body at its lower end. This stem 35 forms a mounting for a gear case C which is rigidly secured to said stem. Disposed within 30 the stem 35 and mounted in upper and lower bearings 36, 37 therein is a tubular counter-shaft 38. A bevel gear 39 housed within the gear case C is secured to the counter-shaft 38. This gear 39 meshes with a bevel gear 40 secured to a 35 propeller shaft 41 journaled in said housing and projecting from the rear thereof, such projecting end of said propeller shaft 41 being fitted with the propeller 42 of the screw type having blades of suitable size, number and pitch. The gear case C, as shown, consists of two shell-like pieces 43 having meeting flanges 44 secured together by 40 means of screws 45. These flanges 44 are formed to provide a boss 46 which receives the stem 35 and, further, to provide aligned bosses 47 to receive bushings 48 for the propeller shaft 41.
45. A rudder 49 issuing from the gear case C, consists of a plate integral with and depending from one of the pieces 43 of said gear case, said plate being located in the plane of the axis of the 50 stem 35. The leading edge of this rudder plate 49 is curved in the manner of a sled runner to cause the rudder to ride over any obstructions it might encounter.
- Near the upper end of the tubular body A, a 55 section thereof is cut-away to expose a portion of the stem 35, the tubular body proper and the terminal portion 50 thereof being tied together by means of a rearwardly projecting web 51 integral with both thereof. Also integrally formed 60 with the terminal portion 50 of said tubular body A is a forwardly projecting flange 52 lying in the same plane as the web 51. Said web 51 provides a handle 53 by means of which the device may be conveniently carried substantially 65 balanced in the natural position of the arm, said web being slotted as at 54 to receive the fingers of a hand and formed with a rib 55 paralleling said slot and conforming to the hand grasping said handle.
70. At the top of the device and branching off from the body A is an elongated transmission housing D including two side members 56 formed with meeting flanges 57 secured together by screws 58. This housing D is secured at one end thereof 75 to the upper end of the body A and projects for-

wardly therefrom. To provide for securing the end of the housing D to the body A, the flanges 51 of the side members 56 are enlarged to form legs 59. These legs 59 are shaped jointly to receive the upper portion of the web 51, the flange 52 and the terminal portion 50 of the tubular body A. Bolts 60 passing through said legs 59 and through said web 51 and flange 52 rigidly connect said housing D to the body A. The housing section formed by the two side members 56 has a bottom opening and about this opening are horizontally disposed connecting flanges 61 formed on said side members 56. Closing said opening is a bottom housing member 62 formed with a continuous flange 63 matching the flanges 61 of the side members 56. Fastening screws 64, passing through the flange 63 of the bottom housing member 62 and through the flanges 61 of the side housing members 56, secure said bottom member 62 to the side members 56. Said flanges 61 of the side members 56 and said flange 63 of the bottom housing member 62 are formed revolvably to receive the cylindrical portions 65 of two coaxially disposed spool-like rotor frames 66. The inner annular flanges 67 of said rotor frames are contained within the transmission housing D and the outer annular flanges 68 thereof are disposed alongside said housing. Coaxially disposed with respect to said latter flanges 68 and secured thereto by means of bolts 69 are the 30 hand wheels 10, each of the two thereof comprising a web 10 and an annular tubular rim 71 forming a continuous hand grip.

Disposed between the inner flanges 67 of the rotor frames 66 is a sprocket wheel 72. Bolts 73 passing through said flanges 67 and said sprocket wheel 72 clamp the latter between said flanges and rigidly secure together said rotor frames 66 and sprocket wheel 72. A center bolt 74 passing through the webs 10 of the hand wheels 10, the 40 rotor frames 66 and sprocket wheel 72, clamps all of said parts together in axially aligned relation.

Intermediately of the transmission housing D and between the side members 56 thereof is a journal 75 having an axial bore therein which 45 receives a mounting bolt 76 passing through said side members 56. Revolvably mounted on said journal 75 and disposed in the plane of the sprocket wheel 72 is a small sprocket wheel 77. Connecting said sprocket wheels 72 and 77 is a 50 sprocket chain 78. Clutched to the sprocket wheel 77 and mounted on its said journal 75 is a large sprocket wheel 79. At the rear of the transmission housing D is a journal 80, similar to the journal 75, a mounting bolt 81, passing through 55 the side members 56 of the housing and through said journal 80, being employed to secure the latter in place with the axis thereof intersecting the axis of the counter-shaft 38 within the tubular body A. Mounted on said journal is a small 60 sprocket wheel 82 which is connected by a sprocket chain 83 to the large sprocket wheel 79 on the journal 75. A bevel gear 84 mounted on the journal 80 and clutched to said small sprocket wheel 82 meshes with a bevel gear 85 on the 65 counter-shaft 38.

From the foregoing, it will be understood that the propeller 42 is rotated in either direction by the hand wheels 10 and that the propeller 42 is appreciably "geared up" through the power transmitting train between said hand wheels 10 and said propeller.

Between the terminal section 50 of the tubular body A and said body proper is a sleeve 86 which is keyed to the stem 35 by means of screws 87 75

(Figs. 1 and 4). At the front of this sleeve 86 is a boss 88 and pivoted on a pintle 89 passing horizontally through said boss 88 is a butt member 90 having a socket 91 in which the end of a steering lever 92 is secured. Said butt member 90 also has a depending lug 93. Compressed between said lug 93 and a seat 94, formed on the sleeve 86, is a helical spring 95 operating yieldingly to press the shoulder 96 on the butt member 90 against the lower side of a quadrant 97 formed integrally with the terminal section 50 of the tubular body A. This quadrant 97 has marginal notches 98 therein for the reception of a latch lug 99 on the butt member 90, when said member is allowed to be swung by the spring 95 into position with the shoulder 96 thereof against the lower face of said quadrant 97. With the butt member 90 interlocked with the quadrant 97, through the medium of the latching lug 99, relative angular movement between the stem 35 and tubular body A is prevented, but when the steering lever 92 is sufficiently depressed against the action of the spring 95 to disengage the latch lug 99 from the notched quadrant 97, the stem 35 may be turned about its axis, through the medium of said steering lever 92, independently of the tubular body A.

Attached to the webs 70 of the juxtaposed coaxially related hand wheels 10 and in diametrically opposed relation are similar hand levers 100 carrying handles 101, said levers being hinged to said wheels and swingable from operative positions (dotted lines, Fig. 5), wherein the handle of each lever is disposed adjacent to the perimeter of its respective wheel, to inoperative positions (solid lines, Fig. 5), wherein the handle of each lever is disposed in shielded position adjacent to the center of its respective wheel. The hinging of each hand lever 101 to its respective wheel 10 is accomplished by means of a hinge pin 102 secured at its ends in companion lugs 103 issuing from the web 70 of the wheel and about which pin the lever may turn. Each lever 101 has relatively offset reaches 104, 105, the reach 105 being received and caught between one pair of spring jaws 106 in the operative position of said lever and the inner reach 104 being received and caught between a second pair of spring jaws 107 in the inoperative position of said lever, said pairs of spring jaws 106, 107 being mounted on the web 70 of the wheel 10 at opposite sides of the hinge pin 102.

The device is readily balanced and carried from place to place with one hand grasping the handle 53. It is easily applied to a boat by lowering the clamp 12 over the edge thereof and tightening the screws 27 against an upright portion of the boat. In normally operative position on a boat, the tubular body A is stationed in substantially upright position with the propeller 42 more or less submerged in the water, according to the selected adjustment of the abutment collars 17 on said body. The upright positioning of the body A is readily acquired by proper adjustment through the medium of the clamping screw 31 and quadrant brace 29. The device is normally clamped to the stern of a boat in line with the keel, the hand wheels 10 being located above and partially forwardly of the rear seat.

For some purposes of use, the steering lever 92 is allowed to remain automatically locked to deprive the tubular body A and stem 35 of relative angular movement and, too, the hand levers 100 on the wheels 10 are swung into their inoperative positions. Under these circumstances,

the clamping screws 15 on the split sleeve 13 are only slightly tightened, whereby the angular relation of the body A relative to the split sleeve 13, will be maintained except for the application of force to the hand wheels 10 in a manner tending to swing said wheels one way or the other. Thus, a user facing the stern of the boat and sitting on a seat in front of the hand wheels 10 may propel the boat by rotating said hand wheels and may, at the same time, steer the boat by swinging said hand wheels 10 one way or the other as may be required. This concurrent rotation and swinging of the hand wheels 10 is readily accomplished since one hand or the other is grasping the annular hand grip 71 of its respective wheel 10 while the other hand is sliding along the other wheel to take a new position for a renewed grip thereon. In steering, by swinging the hand wheels 10 as they are being turned to propel the boat, it may be desirable in view of changing air and/or water currents to alter the angular relation of the stem 35 and body A, which, as above indicated, may be readily accomplished through the medium of the steering lever 92 in changing the interlocking relationship between the butt member 90 and the quadrant 97. By being able to propel and steer a boat solely through the medium of the hand wheels 10, or even one thereof, a user may conveniently and quietly follow a shore line while fishing, hunting with gun or camera, or while sightseeing. The ability to quickly change the course of a boat by means of the hand wheels 10, which also are used to rotate the propeller 42, provides for the convenient maneuvering of the boat about docks and other landings and it affords protection against collision with objects discovered hard by in the travel of the boat.

Under a condition in which the user wishes to occupy the rear seat of the boat and dispense with steering through the medium of the hand wheels 10, he will rigidly clamp the body A in the split sleeve 13 with the near hand wheel 10 conveniently positioned. The hand lever 100 on that wheel will be swung into its operative position and the wheel rotated thereby while the steering of the boat is effected by means of the steering lever 92, depressed for freedom of movement or from time to time shifted from one latched position thereof to another, as may be required.

Under conditions requiring the application of relatively great power to the propeller 42 the hand levers 100 on both wheels 10 may be swung into their operative positions and manipulated, one by one person and the other by a second person, one of such persons, in such case, handling the steering lever 92 to guide the boat.

The device proper may be tilted on the clamp 12 and held by the quadrant 29 and the screw 31 in such position to keep the propeller 42 and rudder 49 from striking bottom in shallow water and also to reduce the "drag" of the propeller while drifting, or when the boat is being propelled by means of oars or paddles.

Changes in the specific form of my invention, as herein disclosed, may be made within the scope of what is claimed without departing from the spirit of my invention.

Having described my invention, what I claim as new and desire to protect by Letters Patent is:

1. A unitary boat propelling device comprising a tubular body, a stem fitted into and revolvably supported by said body, a propeller carried by said stem, a mounting for supporting said body on a boat with the propeller submerged in the water.

floating the boat, said tubular body having an upper terminal portion spaced above the body proper, power supplying means mounted on said terminal portion of said body and connected with said propeller for driving the same, a latching member on said terminal portion of the body, a sleeve encircling and secured to said stem between the body proper and said terminal portion thereof, a butt member pivoted to said sleeve for vertical swinging movement, a latching device on said butt member selectively engageable with said latching member in different positions relative thereto, yielding means acting on said butt member and reacting against said sleeve to move the butt member and engage the latching device thereon with said latching member, and a handle secured to the butt member and serving two purposes, one to move the butt member against the action of said yielding means and release the latching device thereon from said latching member, and the other to turn the stem relative to the body, when the latching device on said butt member is freed from said latching member on said body.

2. A unitary boat propelling device comprising a tubular body, a tubular stem fitted into and revolvably supported by said body, a mounting for swivelly supporting said body in upright position on a boat with the lower end of said stem submerged in the water floating the boat, a propeller carried by said stem at said lower end thereof, a transmission housing branching off from the upper end of said body and providing a lever for turning the body in said mounting, a pair of coaxially disposed hand wheels mounted on the free end of said housing and accessible to an occupant of the boat, power transmitting means extending through said housing and stem and connecting said hand wheels with said propeller for driving the latter from the former, said hand wheels serving, through said housing, to swivel the body in said mounting and thereby change the relation of the propeller with respect to the boat for steering purposes.

3. A unitary boat propelling device comprising a tubular body, a tubular stem fitted into and revolvably supported by said body, a propeller carried by said stem, a mounting for swivelly supporting said body on a boat with the propeller submerged in the water floating the boat, hand operated means carried by said body in position accessible to an occupant of the boat, power transmitting mechanism connecting said hand operated means with said propeller for driving the latter from the former, a portion of said mechanism being disposed within said tubular stem, said hand operated means serving to turn the body in said mounting and thereby change the relation of the propeller with respect to the boat for steering purposes, a hand lever for turning said stem relative to said body, and latching means for securing the stem in selected angular

positions with respect to the body, said hand lever serving to release said latching means.

4. A unitary boat propelling device comprising a tubular body, a tubular stem fitted into and revolvably supported by said body, a propeller carried by said stem, a mounting for swivelly supporting said body on a boat with the propeller submerged in the water floating the boat, hand operated means carried by said body in position accessible to an occupant of the boat, power transmitting mechanism connecting said hand operated means with said propeller for driving the latter from the former, a portion of said mechanism being disposed within said tubular stem, said hand operated means serving to turn the body in said mounting and thereby change the relation of the propeller with respect to the boat for steering purposes, a hand lever for turning said stem relative to said body and latching means for securing the stem in selected angular positions with respect to said body.

5. A unitary boat propelling device comprising a tubular body, a stem fitted into and revolvably supported by said body, a propeller carried by said stem, a mounting for supporting said body on a boat with the propeller submerged in the water floating the boat, power supplying means carried by said body, power transmitting mechanism connecting said power supplying means with said propeller for driving the latter from the former, a hand lever for turning said stem relative to said body, and latching means for securing the stem in selected angular positions with respect to the body, said hand lever serving to release said latching means.

6. A unitary boat propelling device comprising a tubular body, a stem fitted into and revolvably supported by said body, a mounting for supporting said body in upright position on a boat with the lower end of said stem submerged in the water floating the boat, a propeller carried by said stem at said lower end thereof, a pair of juxtaposed coaxially arranged hand wheels carried by said body and accessible to an occupant of the boat, power transmitting means connecting said hand wheels with said propeller for driving the latter from the former, and means for turning said stem to change the relation of the propeller with respect to the boat for steering purposes.

7. A unitary boat propelling device comprising a body, a propeller carried thereby, a mounting for supporting said body on a boat with the propeller submerged in the water floating the boat, said body being angularly adjustable in said mounting, a pair of juxtaposed coaxially related hand wheels, carried by said body in position accessible to an occupant of the boat, and power transmitting means connecting said hand wheels with said propeller for driving the latter from the former.

NELS H. NELSON.
